[57] CLAIM

The ornamental design for a adjustable base for a high chair, as shown and described.

DESCRIPTION

FIG. 1 is a front perspective view of a first embodiment of the adjustable base for a high chair of our new design shown in an extended position;

FIG. 2 is a left side elevation view thereof;

FIG. 3 is a bottom plan view thereof;

FIG. 4 is a view looking upward from plane 4—4 of FIG. 2;

FIG. 5 is a top plan view thereof;

FIG. 6 is a front perspective view of the first embodiment, in a retracted position;

FIG. 7 is a front perspective view of a second embodiment of the adjustable base for a high chair of our new design, shown in the extended position;

FIG. 8 is a left side elevation view of the second embodiment of our design;

FIG. 9 is a bottom plan view of the second embodiment of our design;

FIG. 10 is a view looking upward from plane 10—10 of FIG. 8;

FIG. 11 is a top plan view of the said embodiment of our design; and,

FIG. 12 is a front perspective view of the second embodiment of our new design, shown in the retracted position.

The broken lines appearing in the above figures are for environmental purposes only and form no part of the claimed design.
